No. 36,763.

Patented February 2, 1904.

UNITED STATES PATENT OFFICE.

CHARLES J. DALE, OF PLATTSBURG, NEW YORK.

DESIGN FOR A SOUVENIR SPOON.

SPECIFICATION forming part of Design No. 36,763, dated February 2, 1904.

Application filed September 29, 1903. Serial No. 175,097. Term of patent 7 years.

To all whom it may concern:

Be it known that I, CHARLES J. DALE, a citizen of the United States, residing at Plattsburg, in the county of Clinton and State of 5 New York, have invented a new, original, and ornamental Design for a Souvenir Spoon, of which the following is a specification, reference being had to the accompanying drawing, forming part thereof.

10 The figure is a plan view of a souvenir spoon showing my new design.

What I claim as new, and desire to secure by Letters Patent, is—

The ornamental design for a souvenir spoon, as shown.

CHARLES J. DALE.
